UNITED STATES PATENT OFFICE

166,461

BOTTLE

John H. Funkey, Baltimore, Md., assignor to Carr-Lowrey Glass Co., Baltimore, Md.

Application February 7, 1950, Serial No. 7,787

Term of patent 14 years

(Cl. D58—8)

To all whom it may concern:

Be it known that I, John H. Funkey, a citizen of the United States of America, residing at Baltimore in the State of Maryland, have invented a new, original, and ornamental Design for a Bottle, of which the following is a specification, reference being had to the accompanying drawing, forming part thereof.

Figure 1 is a perspective view of a bottle, showing my new design.

Figure 2 is a transverse sectional view through the lower portion of the bottle taken on line 2—2 of Figure 1.

I claim:

The ornamental design for a bottle, as shown.
JOHN H. FUNKEY.
